ELECTRICALLY DRIVEN HOSPITAL CHAIR

Glenn A. Steven, Kansas City, Kans., assignor to
 The Electro-Glide Company, Inc., Kansas City,
 Kans., a corporation of Kansas

Application June 9, 1947, Serial No. 753,544

7 Claims. (Cl. 180—27)

1
 This invention relates to new and useful improvements in a hospital chair, and has particular reference to hospital chairs of the motor driven type.

The principal object of the present invention is the provision of a motor driven hospital chair wherein the functions of starting, stopping, braking, reversing, steering, and speed regulation are accomplished by the manipulation of a single control lever.

Another object is the provision of an electrically driven hospital chair wherein the operation of both electrical and mechanical control devices is controlled by a single control lever.

Another object is the provision of a hospital chair which is electrically driven and mechanically steered, the driving and steering means being both operated by a single control lever.

Another object is the provision, in a hospital chair of the class described, of brakes adapted to be applied automatically whenever the rider releases the control lever.

Still another object is the provision of a hospital chair supported by two front wheels and a rear tiller wheel, said tiller wheel being oscillatable to steer said chair.

Other objects are simplicity and economy of construction, ease and convenience of operation, and adaptability for use by very seriously disabled invalids.

With these objects in view, as well as other objects which will appear during the course of the specification, reference will now be had to the drawings, wherein:

Figure 1 is a side elevation of a hospital chair embodying the present invention.

Fig. 2 is a plan view of the chair.

Fig. 3 is a horizontal section taken on line III—III of Figure 1, with some parts broken away and others left in elevation.

Fig. 4 is an enlarged fragmentary vertical section taken on line IV—IV of Figure 3, with parts left in elevation.

Fig. 5 is a fragmentary vertical section taken on line V—V of Figure 3, with the battery charger removed.

Fig. 6 is an enlarged fragmentary section taken on line VI—VI of Figure 1.

Fig. 7 is an enlarged vertical section of the control unit, taken on line VII—VII of Figure 6.

Fig. 8 is a reduced section taken on line VIII—VIII of Figure 7.

Fig. 9 is a reduced section taken on line IX—IX of Figure 7.

Fig. 10 is a fragmentary section taken on line X—X of Figure 8.

2
 Fig. 11 is a sectional view taken on line XI—XI of Figure 8.

Fig. 12 is a schematic wiring diagram of the chair, also showing schematically the mechanical operation of the motor brakes.

Like reference numerals apply to similar parts throughout the several views, and the numeral 14 applies to the main frame constructed in the showing contained in the drawings of tubular metal stock. Said frame includes a substantially rectangular lower frame 16 having a planar foot rest 18 fixed in the forward end thereof and being shaped to present an outwardly extending arcuate curve 20 at the rearward end thereof, said curve permitting the oscillatory movement of tiller wheel 22. A substantially semi-circular frame member 24 is fixed to each side of lower frame 16 adjacent the forward end thereof, and extends upwardly to encircle a main wheel 26. Lower frame 16 is cut out between the lower ends of frame member 24 to permit said wheels to be set inwardly. The gaps caused by thus cutting out the lower frame are closed by rigidly connecting angle irons 28 along the inner edges of said frame as shown in Figures 4 and 5.

A substantially U-shaped horizontal upper frame 30 is rigidly fixed at its forward ends to semi-circular members 24, and at its rearward end supports a bearing member 32 adapted to carry vertical shaft 34 for oscillation therein. Said shaft carries a downwardly extending bifurcated member 36 between the arms of which tiller wheel 22 is carried for rotation. Bearing 32 is vertically above the center of curvature of arc 20 of lower frame 16. A brace member 37 rigidly connects the upper and lower frames at the rearward ends thereof.

Bars 38 rigidly fastened to the inner surface of semi-circular members 24, as shown in Figure 5, are in substantial horizontal alignment with upper frame 30. An upwardly extending back support 40 is rigidly attached to each side of upper frame 30 intermediate its ends, and a cross bar 42 extends between the upper ends of said supports. Chair back 44 is fastened to said cross bar. A cushioned chair seat 46 is supported on members 48 extending horizontally between bars 38.

An arm rest support 50 is rigidly attached at one end to each of back supports 40, and at its opposite end to semi-circular member 24. A padded arm rest 52 is secured to each of supports 50 by means of brackets 54.

The space between upper frame 30 and lower frame 16 is substantially enclosed by side panels 56, a rear panel 58 spaced forwardly from tiller

wheel 22, and a front panel 60 disposed beneath the forward edge of chair seat 46, said panels being supported by said upper and lower frames. A shelf 62, as shown in Figure 5, extends across the bottom of said enclosure adjacent the rearward end thereof, and serves as a support for storage battery 64, and battery charger 66. A removable cover 68, as shown in Figure 5, extends across upper frame 30 adjacent rear panel 58, and provides access to the battery and charger. A fender 88 is fixed to each side panel 56, and extends outwardly above the adjacent main wheel 26.

A horizontally extending lever arm 70 is rigidly fixed to bifurcated member 36 carrying tiller wheel 22. A connecting rod 72 is pivotally connected to the free end of said lever, extends forwardly through a hole 74 provided therefor in rear panel 58, and is pivotally connected at its forward end to one arm of a bell-crank lever 76. Said lever is pivotally mounted at 78 to a plate 80 rigidly fixed between the upper and lower frames at the right side thereof. A connecting rod 82 is pivotally connected to the other arm of bell-crank lever 76, extends upwardly through cover 68, and is pivotally connected at its upper end to a crank arm 84 rigidly fixed to the rearward end of a shaft 86, as best shown in Figure 6. Said shaft extends forwardly through right arm rest support 50, and is adapted to be oscillatably rotated therein. Control switch housing 90 is rigidly fixed to the forwardly extended end of said shaft. Thus, whenever said switch housing is manually oscillated to turn shaft 86, crank arm 84 will operate connecting rod 82, bell-crank 76, connecting rod 72, and lever arm 70 to turn tiller wheel 22.

Each of main wheels 26 is mounted on a shaft 92 journaled in a bearing 94 which extends through a hole 96 in side panel 56 and is carried by a gear reduction box 98. Said gear box is rigidly fixed to a pair of bars 100 extending vertically between and fixed at their opposite ends to angle iron 28 and horizontal bars 38.

A gear 102 is rigidly fixed to the inner end of each shaft 92 within gear box 98, and is adapted to mesh with a gear 104 fixed on an intermediate shaft 106 journaled in said gear box as shown in Figure 4. A larger gear 108 is also fixed to shaft 106, and meshes with a pinion 110 fixed on shaft 112 of motor 114. Said motor is rigidly fixed to gear box 98. It will be noted that since the above named gears are substantially in line, motor 114, and motor 115 driving the other wheel 26, are offset from wheel shafts 92. In the showing made, this offset is upward for one wheel and rearward for the other wheel, thus avoiding interference between the motors.

Motors 114 and 115 are of a standard type having brakes incorporated therein. Referring to the schematic showing in Figure 12, it will be seen that there is a friction disc 116 fixed to and rotatable with motor shaft 112 within the motor housing. Another friction disc 118 secured against rotation but movable longitudinally to the motor shaft, is normally urged against rotatable disc 116 by springs 120, thus applying a braking force to the rotation of shaft 92. A solenoid 122 is adapted to draw disc 118 out of contact with disc 116 against the pressure of springs 120 whenever electric current is supplied thereto.

Referring to Figure 3, an electrical connector fixture 124 is fixed in rear panel 58. Any suitable source of electric current may be conven-

iently connected therein to supply current to battery charger 66 through wires contained in cable 126. To front panel 60 are fixed a power switch 128 and a box 130 containing the necessary relays and resistors as hereinafter described. The numeral 132 applies to conduits containing wires for supplying current from battery 64 to motors 114 and 115. Referring to Figure 5, it will be seen that a branch 134 of said conduit passes outwardly through a hole 136 provided in front panel 60 and enters an arm rest support 50 adjacent the point said support is fixed to semi-circular frame member 24. Said conduit extends upwardly through said support and emerges therefrom at a point spaced rearwardly from control switch housing 90, as shown in Figure 1. The conduit then extends forwardly, is fixed to said switch housing adjacent shaft 86 by a bracket 138, and thence enters the switch housing through hole 140, as shown in Figure 9. This arrangement of conduit 134 permits the oscillation of switch housing 90 to steer the chair as previously described without undue twisting of the conduit.

Referring to Figures 6 to 12, it will be seen that housing 90 contains a compound switch 142. Said housing is substantially flat, and has an oscillatable shaft 144 extending substantially therethrough adjacent the lower edge thereof and carried in bearing portions 146 thereof. A hand lever 148 is fixed to the extended end of said shaft outside of the housing by means of a collar 150. Said lever is constantly urged toward a central or neutral position by means of a leaf spring 152, and the oscillatory movement of said handle is limited by a pair of stops 154 secured to housing 90 adjacent the upper edge thereof.

A contact knife 156 is rigidly mounted on shaft 144 within housing 90, and is adapted to move coextensively with hand lever 148. The upper end portion of said knife contact is adapted to move between and in sliding contact with a pair of parallel spaced apart bars 158, said bars being rigidly carried by and electrically connected to housing 90. A plate 160 of insulating material is fixed rigidly in housing 90 parallel to the arc of movement of knife contact 156. A series of spring contacts, numbered 162, 164, 166 and 168, are fixed to said insulator plate along each side of contact knife 156 by means of bolts 170, as best shown in Figure 8, so that they will be contacted by knife 156 whenever it is reciprocated as described. Corresponding contacts of each series are spaced equally from the central position of knife 156, and the contacts of each series are spaced apart from said central position at graduated distances so that knife 156 will contact them in succession, not simultaneously. Corresponding contacts of each series are connected by a series of bars 172 extending between bolts 170 on the opposite side of insulator plate 160, as best shown in Figure 9. An additional spring contact 174 is provided at one side of knife 156, the knife contacting said spring contact only when the knife is moved in one direction. This contact provides for reversal of the motors.

Referring to Figure 12, it will be seen that whenever a suitable electric current is supplied to connector 124 as described, current will be supplied through wires 176 and 178 to battery charger 66. Charging current passes from said charger through wire 180, and through wire 182, wire 184, and wire 186 to storage battery 64. As long as knife contact 156 remains in a neutral position,

no current will flow, since switch 142 and relays 188, 190 and 192 are open. At this time the brakes also are applied, since solenoids 122 are not energized. When the occupant of the chair desires to move forwardly, he moves hand lever 148 forwardly, thus moving knife 156 forwardly, or to the left as viewed in Figure 12. The knife first touches contact 162, and current then flows from battery 64 through wire 194, contact 162, knife 156, conductor 196, and conductor 198 to brake solenoids 122, and thence through wire 186, and wire 200 to battery 64. The solenoids, thus energized, will separate friction discs 116 and 118 as previously described to release the brakes. Since leaf spring 152 will return knife 156 to neutral whenever hand lever 148 is released, and since solenoids 122 will then become de-energized and cause the brakes to be re-applied, an important safety precaution is thereby accomplished. In the embodiment shown, the frame 14 serves as conductors 196 and 198, since knife 156 and solenoids 122 are grounded to said frame.

Knife 156 next touches contact 168, current then flowing from the battery through wire 194, contact 162, knife 156, contact 168, wire 202, the coil of relay 192, wire 205, wire 182, and wire 184 to common return 186. Relay 192 is thus closed, and current flows from wire 194 through wire 206, wire 208, relay 192, wire 210, resistor 212, resistor 214, common feed wire 216, wire 218, armature windings 220 of motor 115, wire 222, power switch 128, wire 224, armature windings 226 of motor 114, wire 228, and wire 230 to common return 186. The armature windings are thus connected in series, and consequently each armature is subjected to about one-half of the battery voltage not consumed by resistors 212 and 214. If switch 128 is thrown to the position opposite from that shown in Figure 12, current flows from common feed wire 216 through wire 218, armature windings 220, wire 222, switch 128, and wire 230 to common return 186, and also from common feed wire 216 through switch 128, wire 224, armature windings 226, and wire 230 to common return 186. The armature windings of the two motors are thus connected in parallel, and each is subjected to the full battery voltage not consumed by resistors 212 and 214. The speed of the motors and the chair is thus increased. It is contemplated that switch 128 be used only when substantial speed changes are desired, for example to use the series connected armatures for indoor use and the parallel connected armatures for outdoor use.

The field windings of the motors are energized from common feed line 216 through wire 232 and a double pole-double throw relay 234 normally having the position shown in Figure 12. With the relay in this position, current flows from wire 232 through the relay, wire 236, wire 238, and 240 to field windings 242, and thence through wires 244 and 246, relay 234 and wire 248 to common return 186. Motors 114 and 115 will then turn wheels 26 through the reduction gearing above described to move the chair forwardly. However, if knife 156 is moved rearwardly, or to the right as viewed in Figure 12, it will touch the reversing contact 174 before it touches any of the contacts 164, 166 or 168. Current will then flow from the battery through wire 194, contact 162, knife 156, contact 174, wire 250, through the coil of relay 234, thence through wires 252 and 248 to common return 186. With relay 234 thus actuated, the field current of the motors will flow from common feed wire 216 through wire 232, relay 234, wires 244 and 246, field windings 242,

wires 238 and 234, wire 236, relay 234, and wire 248 to common return 186. The direction of current flow through field windings 242 is thus reversed by relay 234, and the motors will thus be caused to turn in a reverse direction.

Whenever knife 156 is moved far enough in either direction to touch contact 166, battery current will flow through wire 194, contact 162, knife 156, contact 166, wire 254, the coil of relay 190, wire 256, wire 182, and wire 184 to common return 186. Relay 190 then being closed, current flows through wire 194, wire 206, wire 258, relay 190, wire 260, and resistor 214 to common feed wire 216, and thence to motors 114 and 115 as previously described. Since only one resistor is then in the circuit, a higher voltage is supplied to said motors and a higher speed results.

Whenever knife 156 is moved still farther in either direction and touches a contact 164, current will flow from the battery through wire 194, contact 162, knife 156, contact 164, wire 262, the coil of relay 188, wire 182, and wire 184 to common return 186. Since relay 188 is then closed, battery current flows through wire 206, relay 188, and wire 264 to common feed wire 216, and thence to the motor windings as previously described. Since neither of the resistors 212 or 214 are then in the circuit, substantially the full battery voltage will be applied to the motor windings, and a still higher motor speed will result.

While a three-step speed control has been described, it is apparent that more steps could be utilized to provide a smoother, finer control without departing from the spirit of the invention.

Thus it appears that a hospital chair has been produced wherein all control functions, both mechanical and electrical, have been concentrated in a single manually operable hand lever 148. The functions include starting, stopping, braking, reversing, and speed control. The operator of the chair grasps hand lever 148. By moving it forwardly, the brakes are released and the chair driven forwardly, speed being determined by the amount the hand lever is moved. Rearward movement of handle 148 will cause the chair to be driven rearwardly, with the same speed control. Whenever the hand lever is moved to its central or neutral position, the brakes are applied automatically. As a safety measure, spring 152 is provided to return hand lever 148 to neutral whenever the occupant releases said hand lever due to fainting or other sudden disability. By oscillating the hand lever to the right or left, the chair may be steered as desired.

While hand lever 148 is shown disposed conveniently to the right hand of the chair's occupant, it is apparent that it could be placed in position to be operated by either hand, or by the feet, without departing from the invention. Its adaptability to invalids of many classes is further increased by the fact that operation of the chair requires no finger action, and only a very limited degree of movement.

These and many other minor changes of construction and arrangement of parts could manifestly be made without departing from the spirit of the invention, and it is therefore desired to be limited only by the scope of the appended claims.

I claim:

1. A hospital chair having wheels and electric motors for driving said wheels, means controllable by electric switches for supplying operating current to said motors, a manually operable lever having a neutral or inoperative po-

sition carried by said chair and operable by movement away from its neutral position to close said switches to operate said motors, mechanical brakes normally applied to said motors by spring pressure, electrical means independent from said motor circuit to release said brakes, said lever being operable during its initial movement to actuate said last named electrical means to release said brakes before said motors are started.

2. A hospital chair having wheels and electric motors for driving said wheels, means controllable by electric switches for supplying operating current to said motors, a manually operable lever having a neutral or inoperative position carried by said chair and operable by movement away from its neutral position to close said switches to operate said motors, mechanical brakes normally applied to said motors by spring pressure, electrical means independent from said motor circuit to release said brakes, said lever being operable during its initial movement to actuate said last named electrical means to release said brakes before said motors are started, and resilient means urging said lever toward its neutral position.

3. A hospital chair having wheels and electric motors for driving said wheels, means controllable by electric switches for supplying operating current to said motors, a universally oscillatable lever having a neutral or inoperative position carried by said chair and operable by movement in a first plane from its neutral position to close said switches to operate said motors, mechanical means operable by the pivotal movement of said lever in a plane transverse to said first plane for steering said vehicle, mechanical brakes normally applied to said motors by spring pressure, electrical means controllable by an electrical switch to release said brakes, said lever being operable during its initial movement in said first plane to close said brake releasing switch before said motor switches are closed, and resilient means urging said lever toward its neutral position in said first plane.

4. In a hospital chair having two drive wheels and an electric motor for driving each of said wheels, an electric circuit for supplying current to said motors and including electric switches, a lever carried by said chair for movement from a neutral position to an operative position whereby said switches are closed to energize said motors, brakes mechanically applied to each of said motors by spring pressure, an electric circuit independent of said motor circuit and including means for releasing said brakes, an electric switch for closing said brake circuit to release said brakes, said switch being operable by said lever at a position intermediate its neutral position and its motor energizing position, and resilient means urging said lever toward its neutral position.

5. In a hospital chair having an electric motor for turning each of the drive wheels thereof and a storage battery for supplying current to said motors, a plurality of series-connected resistors in the circuit between said battery and said motors, a brake normally applied to each of said motors by spring pressure, an electric circuit independent of said motor circuit and including means for releasing said brakes, a control lever carried movably by said chair, said lever having a neutral position, electrical switching means operable by the movement of said lever away from its neutral position to successively close said brake circuit to release said brakes, close

said motor circuit to energize said motors, and successively remove said resistors from the motor circuit, and resilient means urging said lever toward its neutral position.

6. In a hospital chair having an electric motor for turning each of the drive wheels thereof and a storage battery for supplying current to said motors, a plurality of series-connected resistors in the circuit between said battery and said motors, a brake normally applied to each of said motors by spring pressure, an electric circuit independent of said motor circuit and including means for releasing said brakes, a control lever carried movably by said chair, said lever having a neutral position, electrical switching means operable by the movement of said lever in one direction from its neutral position to successively close said brake circuit to release said brakes, close said motor circuit to turn said motors in one direction, and successively remove said resistors from the motor circuit, said switching means being operable by the movement of said lever in the opposite direction from its neutral position to successively close said brake circuit, close said motor circuit to turn said motors in a reverse direction, and successively remove said resistors from said motor circuit, and resilient means urging said lever toward its neutral position.

7. In a hospital chair having an electrical motor for turning each of the drive wheels thereof, a brake normally applied to each of said motors by spring pressure, an electrical circuit for furnishing current to said motors, a plurality of series-connected resistors in said motor circuit, an independent electrical circuit including means for releasing said brakes, an oscillatable ground-engaging tiller wheel for steering said chair, a housing carried for rotary oscillation by said chair and operable by said oscillation to control said tiller wheel, a lever carried by said housing by means of which said housing may be turned to control said tiller wheel, said lever being manually oscillatable relative to said housing on an axis at right angles to the axis of said housing, electrical switching means carried in said housing and operable by the oscillation of said lever to successively close said brake-releasing circuit, close said motor circuit, and successively remove said resistors from the motor circuit, and resilient means urging said lever to a position wherein both the brake-releasing and motor circuits are opened.
